NIGHT DEPOSITORY THEFTPROOF
CLOSURE CONSTRUCTION

Herbert C. Behrens, Canton, and Herbert C. Badenell, Navarre, Ohio, assignors to Diebold, Incorporated, Canton, Ohio, a corporation of Ohio

Application November 23, 1948, Serial No. 61,572

3 Claims. (Cl. 232—44)

1

The invention relates generally to night depositories which are used by banks to permit deposits after business hours, and more particularly to a night depository construction which has novel and improved means for preventing access to the deposits by an unauthorized person through the exterior of the depository.

Conventional night depositories include a door which is unlocked by the depositor's key and swings outwardly about its bottom edge to give access to a hopper attached to the door and adapted for receiving a deposit bag, the hopper being arranged when the door closes to dump the bag into a chute communicating with a depository safe. However, there are several ways that deposits may be stolen from such a depository by an unauthorized person having in his possession a key to the depository door.

For example, by opening the door only part way a wire can be inserted past the inner end of the hopper and into the chute, and by attaching a hook on the end of the wire before inserting it, it is possible to catch the hook on a bag in the safe and draw the bag up into the hopper where it is accessible by further opening the door. Another way is to suspend an open-mouth bag or net in the chute just below the hopper by inconspicuous wires extending through the hopper and the door, so that when a deposit bag is dumped from the hopper it is caught in the suspended bag which subsequently can be pulled by the thief into the hopper by the wires with the door partly open, and the bag can then be removed.

These and other methods of burglarizing or pilfering conventional night depositories are made possible by the fact that when the door is fully closed the inner end of the hopper necessarily is spaced far enough from the chute wall to dump a deposit bag, and when the door is slightly open the hopper still clears the chute wall sufficiently to permit feeding a wire past the hopper and into the chute. In other words, there is a position with the door partly open when there is a through opening from the door into the chute.

It has been proposed to overcome this difficulty by providing a door or flap normally closing the inner end of the hopper in such manner as to permit a bag to drop from the hopper, but to prevent a bag from being pulled back into the hopper, but such a door can easily be wedged open by reaching in through the door when partially open.

Obviously, complicated mechanisms for burglar-proofing the conventional night depository can

2

be devised, but such mechanisms are much too expensive for the particular market in which the depositories are sold, and moreover, they are not adapted for use with the present type of conventional depository without completely redesigning the entire construction.

It is a general object of the present invention to provide novel and improved means for making a conventional night depository theft-proof.

Another and more specific object is to provide novel means for preventing the occurrence of a through opening from the outer door into the chute at any time during the opening and closing of the door.

Another object is to provide novel means for closing the inner end of the hopper when the door is open and for closing the front or outer end of the hopper when its inner end is open.

A further object is to provide novel closure means for closing the inner end of the hopper when the door is open, which means cannot be wedged open with the door in open or partly open position.

Another object is to provide novel closure means for the inner end of the hopper so constructed that the door cannot be fully closed if the closure means is wedged shut.

A still further object is to provide novel closure means for the inner end of the hopper so constructed that the door cannot be opened if the closure means is held open.

These and other objects are accomplished by the parts, constructions, arrangements and combinations which comprise the present invention, the nature of which is set forth in the following general statement, and preferred embodiments of which are set forth in the following description and illustrated in the accompanying drawings, and which are particularly and distinctly pointed out and set forth in the appended claims forming part hereof.

In general terms, the present invention may be set forth as including, in a depository having a hopper mounted on the inside of a door hinged at its bottom edge for dumping into a chute when the door closes, a gravity hung closure flap pivoted on the hopper for closing its inner end and being positively held closed by the depository frame during the final opening movement of the door, and an outer cover pivoted on the hopper for closing its outer end and positively held closed by the depository frame for closing the outer end of the hopper in all except the fully open position of the door.

Referring to the drawings forming part hereof

in which preferred embodiments of the invention are shown by way of example;

Figure 1 is a cross sectional view showing the improved depository construction mounted in a masonry wall, with the door in fully closed position;

Fig. 2 is a similar view showing the door in fully open position;

Fig. 3 is an enlarged fragmentary sectional view as on line 3—3, Fig. 2;

Fig. 4 is a sectional view similar to Fig. 1, showing the door in slightly open position;

Fig. 5 is a similar view showing the door approaching fully open position;

Fig. 6 is a fragmentary plan sectional view as on line 6—6, Fig. 2;

Fig. 7 is an enlarged fragmentary sectional view taken substantially on line 7—7, Fig. 2;

Fig. 8 is a fragmentary cross sectional view similar to Fig. 2, as on line 8—8, Fig. 9;

Fig. 9 is a fragmentary sectional view as on line 9—9, Fig. 8; and

Fig. 10 is a fragmentary view as on line 10—10, Fig. 1.

The improved night depository construction is shown mounted in a usual fashion in an opening 10 provided in a masonry building wall indicated at 11. The depository includes an escutcheon door frame 12 overlapping the opening 10, and preferably constructed of strong metal plate having an outer peripheral flange 13 which bears on the outer surface of the wall 11.

The door frame 12 has a central door opening 14 normally closed by a heavy metal door 15 which may be reenforced by a transverse rib 16 and has a bottom rim flange 17. Preferably the door 15 is hinged adjacent its bottom edge by means of pivot pins 18 secured in ears 19 on the side flanges 17a of the door and journaled in suitable bearings formed in the inturned flanges 20 of the door frame (Fig. 6).

A rectangular casing 21 is secured at its upper outer end to the flanges 20 of the door frame, as by screws 22, and the casing extends inwardly and then angularly downward within the wall opening 10, the wall opening being preferably provided with an inclined inner face 23 to accommodate the downwardly inclined part of the casing 21. Within the wall opening, the casing telescopes within the upper end of a downwardly inclined chute 24, being secured thereto by screws 25, and the lower end of the chute communicates with a suitable depository safe (not shown) in a well-known manner.

A substantially L-shaped hopper is mounted on the inside of the door 15, and has a front wall 26 extending transversely of the door 15 and positioned to be inclined slightly outwardly from the door opening when the door is fully open as in Fig. 2. The bottom wall 27 of the hopper is preferably at right angles to the wall 26, and is arranged to be substantially parallel with the inclined bottom wall of the chute 24 when the door is closed and extends at right angles to the inclined walls and across the chute opening when the door is fully open, as shown in Figs. 1 and 2.

The upper end of hopper wall 26 may be connected as shown to an inturned flange 28 formed on a curved top wall 29 which is connected at its front end to the upper part of the door 15, the wall 29 being curved about the pivot 18 as a center. The side walls 30 of the hopper are preferably formed to fit movably inside of the side walls 31 of the casing 21 and preferably

have angular stop plates 32 for engaging suitable bumpers 33 on the frame when the door reaches fully open position. Preferably the upper edges of the hopper side walls 30 are curved about the pivots 18 as centers, and the walls extend outwardly to connect with the door 15 and top wall 29. A notch 30a may be provided in each side wall 30 for engaging a vertical plate 30b welded on the casing 21 when the door is closed.

The door 15 is preferably provided with a lock 34 secured on the inside of the door and having a key cylinder 35 extending through the door for insertion of a key from the exterior thereof. The lock includes a latch 36 which extends upwardly through the curved wall 29 for engaging behind a shoulder 37 on the door frame to lock the door in closed position, as shown in Fig. 1. The exterior of the door is provided adjacent its upper edge with recessed pull handle 38 as shown.

The constructions of the parts thus far described are more or less conventional, and per se form no part of the present invention.

An inner closure flap 40 for the inner end of the hopper is pivoted at its front end on intermediate portions of the hopper side plates 39 adjacent their upper edges. As best shown in Fig. 7, a pivot pin 41 extends between the hopper side plates 30, and a central hinge sleeve 42 on the flap 40 is journaled on the hinge pin. The side edges of flap 40 fit closely within the side walls 30 of the hopper with only a working clearance. A front cover 43 is provided for that portion of the hopper between the hinge pin 41 and the upper end of the front outer hopper wall 26. The rear or inner end of the cover 43 is provided with hinge sleeves 43a which are journaled on the pin 41 and which extend from the ends of the sleeve portion 42 outwardly toward the hopper side walls 30. The cover 43 is curved about the pivot 18 as a center, so that when the cover is closed as in Fig. 1 it becomes a continuation of the arcuate wall 29.

The cover 43 is provided along its side edges with depending flanges 44 having bottom edges curved parallel to the top of the cover, and a downturned flange 45 is provided along the front edge of the cover. The front and side edges of the top of the hopper opening are provided with grooves for receiving the flanges 44 and 45 when the cover is closed, so that there can be no possibility of inserting a wire or the like under the cover 43 in closed position. The grooves for receiving the curved flanges 44 are provided by composite plates indicated generally at 46 which are attached to the hopper side walls 30 by means of rivets 47.

As best shown in Figs. 3 and 7, the plates 46 are composed of three separate plies in flatwise abutment with each other, the outer ply 48 being in abutment with the hopper wall 30, and the inner ply 49 terminating slightly below the tops of the plies 48 and 50 to form a groove 51 along the top edge of the plates 46 for receiving the depending rib 44. As an additional safeguard against possible insertion of a wire into the hopper, the ribs 44 are continued around the under side of the hinge sleeves 43a of the cover, as at 44a, and the intermediate plate 49 is formed to provide a groove for receiving the extended rib 44a.

A channel strip 52 is attached to the inturned flange 28 along the upper front edge of the hopper opening, for providing a groove 53 which receives the downturned flange 45 of the cover

43 in closed position. As shown in Fig. 7, the hinge pin 41 is mounted at its ends in the plates 46 by extending through the outer ply plates 48 thereof, the inner ply plates 50 being curved to seat the hinge sleeves 43a. As best shown in Fig. 3, means for urging the cover 43 toward open position may consist of spring-pressed plungers 54, one in each groove 51, for engaging the ribs 44 to push the cover upwardly an initial amount when the door reaches fully open position, as in Fig. 2. The plungers 54 may be urged upwardly by helical springs 55 slidably mounted in bores 56 in the intermediate plates 49, bottom of the bores being closed by screw plugs 57.

The rear inner end of the flap 40 is provided with a plurality of pointed teeth 58 preferably angled toward the inner end of the bottom hopper wall 27, and arranged to overhang the inner end of the wall 27 when the flap is fully closed thereon, as indicated in Figs. 2, 4 and 5. In fully closed position, the hopper bottom wall 27 is spaced from the front wall of the chute 24 a distance less than the length of the teeth 58, so that when the hopper approaches fully closed position the teeth 58 will engage the chute wall, as indicated at A in dot-dash lines in Fig. 1. The purpose of this construction is to prevent final closing movement of the door without initiating opening movement of the inner end of the flap 40, so that in the event an unauthorized person were to secure the inner end of the flap in closed position to trap a deposit bag for subsequent removal, the depositor would be warned by the failure of the door to close. The flap 40 will normally hang substantially vertical by gravity when the door is fully closed, as shown in full lines in Fig. 1, and a deposit bag will slide from the hopper and push the flap aside sufficiently to drop into the chute. The purpose of the teeth 58 is to guard against any possibility of pulling a bag from the chute upwardly into the hopper by means of wires and the like.

The means for preventing opening of the inner flap 40 during final opening movement of the door, and for holding the cover 43 closed until the door is fully open, preferably consists of a curved wall 60 mounted within the casing 21 above the hopper and curved about the pivot 18 as a center. The wall 60 is secured at its front end 61 to the inner upper flange 62 of the door frame 12, and is secured at its inner end 60a to the rear wall of the casing 21, by suitable means such as spot welding or riveting.

The curved wall 60 is positioned to be very closely adjacent to the curved wall 29 and the front cover 43 when the door is closed, so that there is only a necessary working clearance permitting the hopper to move past the wall 60 as the door is opened. The bend in the flap at the base of the teeth 58 at the inner end of the flap 40 is indicated at 63, and when the flap is fully closed on the hopper wall 27, as in Fig. 2, the bend 63 in the flap is positioned so as to have only a working clearance with the curved wall 60 during final opening movement of the door. Thus, as shown in Fig. 2, when the door is fully open, the bend 63 of the flap is substantially in engagement with the curved wall 60 so that the flap cannot be opened.

As shown in Figs. 4 and 5, the curved wall 60 is in substantial engagement with the cover 43 during most of the opening movement of the door, so that the cover 43 cannot be opened to any extent whatever until the door is substantially fully open or until the rear end of the

cover 43 clears the front end 61 of the curved wall 60. Accordingly, when the door is only slightly open as in Fig. 4, the flap 40 is free to open but the cover 43 is held tightly closed by the curved wall 60, so that no access can be had through the door into the hopper and thence into the chute. As the door is opened farther so that the front edge of the hopper opening clears the door frame, as in Fig. 5, the inner end 61 of the flap 40 is still free to be opened a limited amount, but the cover 43 is still held tightly closed by the wall 60.

When the door reaches or approaches the fully open position of Fig. 2 and the cover 43 clears the door frame, the cover 43 can then be opened, but the bend 63 on the flap 40 is in substantial engagement with the wall 60, thus preventing any opening movement of the flap 40. Obviously, by the time the door has closed sufficiently to permit any opening movement of the flap 40, the cover 43 is in engagement with the curved wall 60 to prevent any opening movement of the cover. Thus there is never a through opening from the outer door to the inner chute in any position of the door.

It is apparent that if the flap 40 should in some way be wedged open, it will not stay in such position during movement of the door, because even though the flap is wedged open only a slight amount, the door cannot be opened sufficiently to allow opening movement of the cover 43 and access to the hopper.

In Figs. 8 and 9 a modified form of improved means is shown for initiating opening movement of the cover 43 as the door reaches fully open position. In the modified form, the casing 21 is provided adjacent the door opening with a depending ear 65 having an inner cam surface 66 thereon. The adjacent side of the cover 43 is provided with a rearwardly extending arm 67 having a roller 68 at its rear end adapted for engaging the cam surface 66 to raise the cover 43 as the door approaches the fully open position of Fig. 2.

In case an unauthorized person should insert a spring plate in the hopper in such manner as to urge the flap 40 to open when it is entirely below the inner end of curved wall 60, as shown at B in dot-dash lines in Fig. 1, for the purpose of pulling a bank deposit bag up into the hopper for subsequent removal, means is provided for preventing opening of the door sufficiently to gain access to the hopper.

As shown in Figs. 1 and 10, the flap 40 is provided with slots 70 in its opposite edges and adjacent to the hinge portions 43a, and a pair of hooks 71 is provided on housing 21, one to enter each slot 70 when the flap 40 is opened to the dot-dash position B, as in Fig. 1. Now if the door 15 is opened very slightly in order to manipulate wires or the like extending into the hopper for raising a deposit bag, the bottom of slots 70 will engage behind the hooks 71, thus positively preventing any further opening movement of the door and hopper and consequently preventing the theft.

The novel depository construction set forth provides simple and inexpensive means for making a conventional night depository theft-proof, without requiring complicated mechanisms which are difficult and expensive to install. The novel construction is so designed as to prevent the occurrence of a through opening from the outer door to the chute at any time during opening and closing movement, consequently precluding any

possibility of access by an unauthorized person to deposits after they have been placed in the hopper and the door has been completely closed.

In the foregoing description, certain terms have been used for brevity, clearness and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention, the construction, the operation and use of preferred embodiments thereof, and the advantageous new and useful results obtained thereby; the new and useful constructions, and reasonable mechanical equivalents thereof obvious to those skilled in the art, are set forth in the appended claims.

We claim:

1. In a night depository having a door hinged at its bottom edge in a casing and a hopper carried on the inside of the door for dumping into a chute when the door closes, an inner closure flap pivoted on an intermediate portion of said hopper and having its inner end overhanging the inner end of said hopper, means on the casing for engaging the inner end of said flap to prevent opening of the flap during final opening movement of the door, an outer cover pivoted on said intermediate portion of the hopper for closing its outer end, and said casing means slidably engaging the cover to prevent opening movement

thereof until the door is fully open, the inner end of said inner flap engaging the chute wall to start opening movement of the flap just before the hopper reaches fully closed position.

5. In a night depository having a door hinged at its bottom edge on a frame and a hopper mounted on the inside of the door for dumping into a chute when the door is closed, an inner closure flap pivoted on the hopper for closing its inner end and having a slot therein, and a projection on the frame for engaging said slot to arrest opening movement of the door when the flap is held in partially open position.

10. In a night depository having a door hinged at its bottom edge on a frame, a chute, and a hopper mounted on the inside of the door for dumping into the chute when the door is closed, the hopper having a bottom wall extending completely across the chute when the door is open, an inner closure flap pivoted on the hopper for closing the hopper, means on said flap for preventing final closing movement of the door if the flap is held completely closed, and a wall on the frame positioned to lie closely adjacent to and substantially engage said closure flap as the hopper is moved toward open position.
